TORPEDO TUBE

Tom Marwood, Hythe, England, assignor to
 Hubert Scott-Paine, Hythe, Southampton,
 England

Application January 14, 1941, Serial No. 374,319
 In Great Britain September 11, 1939

1 Claim. (Cl. 114—238)

A torpedo includes in its mechanism various devices which require adjustment or setting prior to the discharge of the torpedo. These are readily accessible when a torpedo is stored separately from the tube and inserted into the tube immediately before firing, but in some cases, as for example in small high-speed motor torpedo boats, it may be desirable to carry one torpedo permanently in the tube, and in order to make these adjustments, suitably covered openings or doors are provided in the tube to give access to the torpedo inside. It follows, therefore, that the torpedo must be located angularly within the tube so that the various devices to be attended to register with the openings through which access is to be obtained to them. The devices include the gyroscope angling gear, gyroscope control, air lever trip gear, depth setting mechanism, stop valve, operating valve and so forth.

The object of this invention is to provide simple means for locating the torpedo in the tube, and according to this invention the locating means comprises a longitudinal guide inside the torpedo tube having a flared opening which receives a projection on the torpedo, and adjusts the torpedo angularly in the tube as it is pushed in.

Preferably the guide aforesaid is situated near the inner end adjacent the rear door of the tube and engages a side fin or bracket on the torpedo.

Preferably a guide is situated at each side of the tube on a horizontal diameter thereof and each guide is conveniently constituted by a pair of angle irons riveted or otherwise secured inside the tube.

In the accompanying drawing which illustrates one embodiment of this invention, more or less diagrammatically:

Figure 1 is a sectional elevation of the rear end of a torpedo tube, and

Figure 2 is a transverse sectional view on the line 2—2 of Figure 1 to a larger scale.

In the drawing, a portion of the rear end of a torpedo tube is indicated by the reference 10, and its rear door, which is dished inwardly, at 11. The rear end of a torpedo is indicated at 12, and it is provided with the usual brackets 13 which carry the controlling fins.

The guide forming the subject matter of this invention is constituted by a pair of angle irons 14, 15 which are secured on the inner face of the wall of the tube 10 facing one another and spaced apart to receive between them one of the brackets 13. Preferably, there are two of these guides set on a horizontal diameter of the tube 10, and they are secured to the tube in any convenient manner, as for example by the bolts 16. In order to economise space the bolt-heads 17 are cut away as shown, where they abut one arm of the angle piece and the bolts are thereby held against rotation, facilitating the screwing up of the nuts 18.

15 At the rear end of the guide, near the rear door of the tube, the two angle irons are straight and parallel with one another over a length of, say 10 to 12 inches. They extend forwardly for a total length of, say, 25 to 30 inches, and diverge in a forward direction so that at the forward end 19 of the guide they are 5 inches or so apart.

The torpedo is loaded into the tube from the forward end, and when doing so the fins 13 are set approximately in a horizontal position so that 25 when the torpedo is pushed home the lateral brackets enter the flared opening of the guide and are directed into the desired angular relationship as determined by the rear end of the guide which is straight and parallel sided.

20 It is thereby assured that the angular setting of the torpedo is correct in the tube and access can be made by the openings indicated generally by the reference 20 to make any of the adjustments above described.

35 I claim:

In combination with a torpedo tube adapted to receive a torpedo which is provided at its rear end with two diametrically opposite radial fins, two pairs of angle-irons secured to the inside of 40 said torpedo tube near the rear end thereof and each pair adapted to receive between its angle-irons one of the torpedo fins, said angle-irons of each pair being throughout substantial rear portions of their length parallel to one another and 45 to the axis of said torpedo tube and throughout their forward portions diverging from one another.

TOM MARWOOD.
